UNITED STATES PATENT OFFICE.

EDWIN J. SIBLEY, OF WESTBURY, NEW YORK.

COMBINED SHUTTER HOOK AND SPRING.

Application filed February 23, 1927. Serial No. 170,103.

This invention relates to improvements in shutter fastening means, and the particular object of the invention is to provide a new article of manufacture in the form of a combined shutter hook and spring. One object of the invention is to provide the shutter hook and spring adapted to be knocked down or readily disassembled. Another object is to construct the article so that it may be easily 10 assembled and affixed. Still another object is to provide resilient means, such as a spring, for pressing the shutter against the holding hook and thus prevent rattling.

In the drawing accompanying this specification Figure 1 is a front view of a combined shutter hook and spring embodying the invention. Figure 2 is a side view thereof with parts in section. Figure 3 is a view in outline illustrating the advantages of the knock down 20 feature of the invention.

Referring to the drawing, the combined shutter hook and spring comprises a base plate 5 having holes 6 for the passage of screws or nails for affixing it to the wall. The 25 base plate also has a central hole 7 and a centrally disposed slot 8. The numeral 9 denotes a hook bolt, one end 10 of which is threaded and passes through the hole 7 in the base plate. The other end 11 is round and 30 serves as a pivot for the S-hook 12. The extreme outer end 13 is threaded. Nuts 14 and 15 respectively are screwed on the threaded 35 ends of the bolt to secure it in the base plate and to keep the S-hook in position. A washer 16 may conveniently be used to prevent the nut 15 from binding on the hook.

The numeral 18 denotes a suitably curved or coiled spring which is permanently secured to the bolt by a rivet 19. The spring has a tail 40 end 20 adapted to enter the hole 8 in the base plate to prevent the spring from turning on the rivet and also as a matter of appearance. The engagement of the spring and base plate 45 also positions the latter in proper relation to the bolt.

The assembled shutter hook and spring is

shown in Figures 1 and 2, from which it will be apparent that when the article is affixed to the wall in proper relation to a shutter and the latter opened, it will be caught in the usual manner behind the hook 12. In this position the shutter will be pressed against the hook by the spring 18 and held firmly, yet the shutter hook is easily released by a gentle pressure against the spring. 50

Figure 3 illustrates the advantage of the knock down feature of the invention. As seen, the parts are easily disassembled by unscrewing the two nuts and may then be packed neatly in a flat box for convenience in shipping, storing and displaying. Under modern business conditions this is an important economic advantage. 60

The combined shutter hook and spring constructed in accordance with this invention is effective, artistic in appearance and inexpensive in manufacture. 65

I claim:—

1. As a new article of manufacture a combined shutter hook and spring comprising a base plate adapted to be affixed to a wall, a bolt detachably connected to said base plate in angular relation thereto, a shutter hook detachably pivoted on the bolt a distance away from the base plate, a flat curved spring on 70 the bolt interposed between the base plate and the shutter hook, said spring detachably engaging a hole in the base plate to prevent relative rotary movement between the base plate and bolt, said spring extending to one side 75 of the bolt for yieldingly pressing a shutter against the hook.

2. As a new article of manufacture a combined shutter hook and spring adapted to be readily disassembled for shipping purposes 85 comprising a bolt, a base plate detachably connected to one end thereof, a shutter hook detachably pivoted on the other end of the bolt, a spring affixed to the bolt and projecting upwardly therefrom and detachably engaging a hole in the said base plate. 90

EDWIN J. SIBLEY.
